United States Patent Office.

THOMAS K. COOK, OF NEW YORK, N. Y., ASSIGNOR TO HIMSELF AND
EDWARD H. HOTCHKISS, OF SAME PLACE.

Design No. 5,017, dated June 20, 1871.

DESIGN FOR A PIPE-WRENCH.

The Schedule referred to in these Letters Patent and making part of the same.

To all whom it may concern:

Be it known that I, THOMAS K. COOK, of New York, in the county and State of New York, have invented and produced a new and original Design for a Wrench; and I do hereby declare the following to be a full, clear, and exact description of the same, reference being had to the accompanying drawing forming part of this specification, which illustrates a wrench constructed in accordance with my design.

My invention consists in a wrench constructed in one piece, in the form substantially as shown in the drawing, to wit, of the shanks A, upon one or both ends of which is formed a hook, B, whose inner face is provided with teeth C.

The point of the hook is rounded somewhat, and the teeth extend from the shank to about the point d.

The teeth may be either made differential, as shown, or of equal size, and may also be formed with a uniform pitch, or with one face larger than the other.

Having thus described my invention, What I claim as new, and desire to secure by Letters Patent, is—

The design for a wrench, as herein shown and described.

The above specification of my invention signed by me this 2d day of May, 1871.

THOS. K. COOK.
